UNITED STATES PATENT OFFICE

152,933

DESIGN FOR A NASAL BRUSH

Charles Scott Watson, Pocatello, Idaho

Application March 3, 1947, Serial No. 137,288

Term of patent 14 years

(Cl. D83—1)

To all whom it may concern:

Be it known that I, Charles Scott Watson, a citizen of the United States, residing at Pocatello, in the county of Bannock and State of Idaho, have invented a new, original, and ornamental Design for a Nasal Brush, of which the following is a specification, reference being had to the accompanying drawing, forming part thereof.

Figure 1 is a bottom plan view of a nasal brush, showing my new design.

Figure 2 is a side elevation thereof, and

Figure 3 is a top plan view of the same.

I claim:

The ornamental design for a nasal brush, as shown.

CHARLES SCOTT WATSON.
